6 Claims. (Cl. 139—39)

1

This invention relates to pile fabrics and their manufacture by weaving operations, in which pile wires are inserted into the warp shed and pile warp yarns are raised over the wires to form pile elements. More particularly, the invention is concerned with a novel method of weaving a pile fabric, in one form of which the pile elements are arranged in transverse rows and each row includes pile elements in the form of both pile tufts and pile loops, while, in another form, the fabric includes pile loops of two different heights in the same transverse row.

The weaving of pile fabrics on looms provided with pile wires and mechanism for inserting such wires into the shed to elevate pile warp yarns and form pile elements therefrom has been practiced for many years. In conventional looms, in which pile wires are used, the wires are of uniform height from end to end, so that the pile warps raised over each wire are all elevated to the same height. The wires used may be either plain, non-cutting wires or cutting wires provided with knives and, when a plain wire is withdrawn from the row of loops of pile yarn raised over it, it leaves a transverse row of pile loops, all of the same height. Upon withdrawal of a cutting wire, the loops of the pile warps raised over the wire are severed to form tufts lying in a transverse row, all of the tufts being of the same height and each having two legs. In some weaving operations, the set of wires used in a loom includes wires of two or more heights, in which event, the elements of the pile surface are of different heights determined by the height of the wires, over which they are formed, but all the elements lying in a single transverse row are all of the same kind and all of the same height.

Some pile fabrics woven heretofore on looms, in which pile wires are used, have had a pile surface made up of both tufts and loops, and one such fabric, known as "cut and uncut," is woven by the use of a set of pile wires consisting of cutting and non-cutting wires arranged in alternation. In such a fabric, all the pile elements in a single transverse row are of the same kind, either tufts or loops, and, in order to give the pile surface the appearance of having both tufts and loops in the same row, successive rows of pile elements may be left incomplete and with the gaps in one row opposite the filled spaces in the next. When the wires are withdrawn, the tufts and loops expand somewhat, so that the tufts and loops appear to lie in the same row and the desired effect is approximated. However, the pile in such a fabric lacks the density of one,

2

in which each row contains a full complement of pile elements, and the cost of production is higher, since a larger number of loom operations is required to produce a unit length of goods.

- 5 Pile fabrics, in which both tufts and loops are combined in the same transverse row, have been produced heretofore by operations, in which the pile warps are raised over cutting and non-cutting wires arranged in alternation, and the tufts and loops produced on withdrawal of the wires are forced into a single row during the beat-up. Such fabrics are subject to a number of objections, in that, in one variety, the weft yarns are not as tightly beaten up as in conventional fabrics, while, in another, stuffer warps cannot be used and the weft yarns are not bound as tightly in place as in conventional fabrics. In both varieties last described, two sets of pile warps must be used.
- 10 20 The fabric produced by the method of the invention is one having a pile surface made up of pile elements of two kinds, that is, either loops and tufts or loops of two different heights. The fabric differs from and is superior to prior similar fabrics, in that each transverse row of pile elements in the fabric includes a full complement of pile elements, so that the pile density is a maximum and the loom operates at greatest efficiency, only a single set of pile warps is required, so that setting up the loom is simplified, and, in the weaving of the fabric, a single wire is inserted between each two adjacent weft yarns in the upper level, so that the fabric can be tightly beaten up. In the production of the fabric in accordance with the new method, the formation of the tufts or high loops in any transverse row is carried out by raising the desired pile warps over a pile wire in the usual way. The formation of the low loops in the same row as the tufts or high loops is then effected without the use of a wire. In order to produce the fabric, the pile warps are maintained under slack tension, while the remaining warps are under relatively heavy tension. The shedding operation is then modified in such manner that, when a weft yarn, inserted into the shed immediately following that, into which a pile wire was inserted, is beaten up, the weft yarn engages all the pile warps and pushes the warps ahead of it to form relatively low loops. When the weft yarn is fully beaten up, the reed engages the previously inserted wire, which has bent rearwardly under torsion, and causes it to stand erect, so that the pile warps raised over the wire tighten up to form loops of the height of the wire and the low loops formed
- 15 25 30 35 40 45 50 55

by the action of the weft yarn on all the rest of the pile warps remain in position ahead of the yarn as low loops. Ultimately, when the wire is withdrawn, the loops of the pile warps raised over it are either severed to form tufts or remain as high loops and the low loops of all the other pile warps shift slightly forward. As the tufts or high loops and the low loops all rise between the same two weft yarns, that row contains a full complement of pile elements.

For a better understanding of the invention, reference may be made to the accompanying drawings, in which:

Fig. 1 is an expanded view in perspective of one form of the fabric, which can be produced by the method of the invention;

Fig. 2 is an expanded view in perspective of another form of the fabric;

Fig. 3 is a diagrammatic longitudinal view through a loom at one stage in the weaving of the fabric;

Fig. 4 is a fragmentary plan view showing the mounting of the supplies of pile yarn in the loom of Fig. 3;

Fig. 5 is a fragmentary end view of a tensioning element used in the loom;

Fig. 6 is an enlargement of part of Fig. 3;

Figs. 7-10, inclusive are diagrammatic views illustrating the sheds in the four stages of the cycle of weaving the fabric of Fig. 1; and

Figs. 11-15, inclusive are diagrammatic views showing the manipulation of the warps at different stages in the beat-up of a weft yarn inserted into the shed shown in Fig. 9.

The fabric in the form shown in Fig. 1 comprises a backing made up of stuffer warps 21, weft yarns 22, 23 lying, respectively, above and below the stuffer warps, and binder warps 24, 25 in two sets crossing the weft yarns above and below and binding them against the stuffer warps. The binder warps are arranged in pairs, consisting of a warp of each set, lying close together at one side of a group of stuffer warps, shown as four in number, and the adjacent pair or binder warps lies at the other side of the group of stuffer warps, this arrangement continuing across the fabric. Ordinarily, the stuffer warps are stiff yarns of jute or paper, the binder warps are light cotton yarns, and the weft yarns are of cotton and heavier than the binder warps. It is to be understood, however, that the backing illustrated is merely one form of conventional backing and the fabric may have any desired backing, as, for example, one in which the stuffer warps lie in two levels, the weft yarns lie above, between, and below the stuffer warps, and a single set of binder warps is used. In both such backings, adjacent weft yarns in the top level are separated by binder warps passing from one level to the other and, in the fabric illustrated, binder warps of both sets pass between adjacent weft yarns in the top level and cross at about the level of the stuffer warps.

The fabric includes a single set of pile warps 26, which are ordinarily plied wool yarns, and each space in the fabric above a group of stuffer warps and between spaced binder warps contains a single pile warp. Each pile warp is bound in place by portions lying beneath weft yarns and, in the fabric illustrated, each pile warp is bound beneath each weft yarn in the top level. Between each two adjacent weft yarns in the top level, a portion of each pile warp is raised to form a pile element, which may be a loop 27 or a tuft 28 made up of two tuft legs 28a, 28b of

equal length. In the fabric illustrated, the tufts are substantially higher than the loops and, ordinarily, this relationship will prevail, since the loops are always relatively low. However, the tufts may be somewhat lower than is shown, although the tufts will always be sufficiently higher than the loops to permit the ends of the tufts to be sheared in the finishing operation without cutting the bights of the loops.

With the construction described, the fabric differs from prior generally similar fabrics in that there is a full complement of pile elements in each row across the fabric and each such row includes the same number of pile elements, since there is one element in each space defined by adjacent top weft yarns and adjacent pairs of binder warps. Each transverse row may include both tufts and loops and each top weft yarn is bound in place by binder warps passing over that yarn and then from one face of the backing to the other between that yarn and the next adjacent yarn. Because of its construction, the fabric may be tightly beaten up, and it is characterized by having a dense uniform pile without gaps. As the effect of having both tufts and loops in the same transverse row between a pair of top weft yarns is not obtained by omitting tufts from one row and loops from the next and depending upon the beat-up to make it appear that the tufts and loops lie in the same row, the fabric can be made with the loom operating at top efficiency.

The fabric shown in Fig. 2 is similar in construction to that of Fig. 1, except that the pile elements comprise both high loops 29 and low loops 30 lying in the same transverse row. As in the case of the Fig. 1 fabric, that of Fig. 2 may include any conventional backing but has been illustrated, for convenience, as having the same backing as the Fig. 1 fabric.

The weaving of the fabric in accordance with the method of the invention may be carried out on a conventional loom provided with a frame 31 for supporting supplies of pile warps in the form of spools 32 mounted on spindles 33 having their ends received in slots 34 in the walls of the frame. The pile warp 26 on each spool passes around a guide 35 and then over the top of the spool and beneath another guide 36. Between the spool and guide 36, a weight 37 of U-shape rests upon the warp to tension it. In practice of the new method, the tension weights employed are much lighter than those ordinarily used and each spool runs freely on its spindle, instead of with its flanges resting on a felt pad, as is usual. As a result of the use of the lighter weights and the omission of the pads, the pile warps are under relatively light tension. From the guide 36, each pile warp passes through the eye of a cord 38 weighted by a lingo 39 and controlled by a Jacquard mechanism indicated at 40.

The stuffer warps 21 are supplied from a beam 41 and the two sets of binder warps 24, 25 from respective beams 42, 43. The stuffer warps pass from their beam through heddle eyes in a harness frame 44 and binder warps 24, 25 pass from their beams 42, 43 through heddle eyes in respective harness frames 45, 46. The harness frames are cam-actuated and the stuffer and binder warps are maintained under the usual relatively heavy tension.

The loom includes the usual reed 47 mounted on a lay (not shown) and mechanism for inserting pile wires 48. The wires are of conventional

form and may be plain non-cutting wires or knife wires.

In the weaving of a fabric by the new method, the warps are formed into a succession of sheds in a cycle repeating itself, and the number of different sheds in a cycle depends on the construction of the backing. In the weaving of the fabrics of Figs. 1 and 2, each cycle consists of four different sheds and, in each shed in a cycle, into which a pile wire is inserted, the pile warps may all lie in the upper line in the shed, so as to be raised over the wire, some of the pile warps may be raised over the wire and others not, or none of the pile warps may be raised over the wire.

In the first shed of the cycle, shown in Fig. 7, the stuffer warps 24 and binder warps 25 lie in the lower line of the shed and binder warps 24 lie in the central line of the shed. Pile warps 26a, which were raised over wire 48 last inserted, and pile warps 26b, which were not raised over the wire, lie in the lower line of the shed. The wire, which was erect when fully beaten up, has twisted rearwardly after the beat-up to an inclined position by torsion applied thereto by the pile yarns raised over it. The weft yarn 22 has been inserted into the shed and is shown as partially beaten up. In this and other sheds, in which stuffer warps lie in the same line as pile warps, the stuffer warps are displaced slightly downwardly from the pile warps. As a consequence, the weft yarn being beaten up is advanced along the pile warps in contact therewith to the fell of the fabric and it is this contact of the weft yarn with the slack pile warps, which produces the low pile loops 27, as will be presently explained. When the weft yarn has been fully beaten up in the first shed, the previously inserted wire 48 becomes erect, as shown in Fig. 8, so that the pile yarns 26a raised over it form high loops 29. At the same time, the remaining pile yarns 26b, that were not raised over the wire, have been caused to form low loops 27.

In the second shed, Fig. 8, pile warps 26a, which have been selected by the Jacquard mechanism, lie in the upper line of the shed, and all the other pile warps 26b lie in the central line of the shed. Binder warps 24 and stuffer warps 21 also lie in the central line of the shed and binder warps 25 lie in the lower line. Wire 48 has been inserted into the upper part of the shed between the upper and central lines and a weft yarn 23, which is to lie in the lower level of the fabric, has been inserted into the lower part of the shed between the central and lower lines.

The third shed, Fig. 9, is similar to the first, except that binder warps 25 lie in the central line of the shed and binder warps 24 lie in the lower line. Similarly, the fourth shed is the same as the second, except that binder warps 25 lie in the central line of the shed and binder warps 24 lie in the lower line.

In the beat-up of an inserted weft yarn or such a yarn plus a pile wire in a loom equipped with a conventional shedding motion, the harness cams and the Jacquard mechanism are so timed that the harnesses and the Jacquard cords begin to change their positions to close the shed at a time, when the reed is about 1" away from the fell of the fabric, and the warps reach parallelism and begin to form the new shed, when the reed is about $\frac{3}{8}$ " away from the fell. In the practice of the new method, the timing of the shedding motion is advanced, so that the harnesses and Jacquard cords begin to close the shed, when the

reed is, for example, about 2" away from the fell, and the warps reach parallelism, when the reed is about 1" from the fell. This change in the timing of the shedding motion, together with the slack tension maintained on the pile warps, results in the formation of low pile loops in the following manner.

The low pile loops are formed in the first and third sheds in the cycle and the successive stages 10 of the beat-up of the weft yarn inserted into the third shed are illustrated in Figs. 11-15, inc., the elements of the fabric being somewhat separated for clearness. At the first stage of the beat-up of the third shed (Fig. 11), the binder warps 25 lie in the central line of the shed and all the other warps lie in the lower line. Pile warps 26a, which were raised over the wire 48 inserted into the second shed, lie slightly higher in front of the weft yarn 22 than pile warps 26b, which were not raised over that wire. Pile warps 26a and 26b both lie slightly above stuffer warps 21 and binder warps 24 in the lower line and the inserted weft yarn 22, accordingly, lies in light contact with pile warps 26a. When the weft yarn 25 is about 2" from the fell of the fabric, the harnesses and Jacquard cords have moved the pile warps 26a, 26b and the stuffer warps 21 into approximate parallelism, as shown in Fig. 12, with binder warps 25, which have not moved. 30 Immediately, after this stage, the pile warps 26a, which have been selected by the Jacquard mechanism, begin to move into the upper line of the shed.

From the time that the pile warps 26a, 26b and the stuffer warps 21 reach parallelism with the binder warps 25, the weft yarn is caused to press against the pile warps and, as the beat-up continues, the rubbing of the yarn against the pile warps forces portions of those warps ahead of the yarn, as indicated at 26c, 26d, Fig. 13. The portions of the pile warps thus being pushed ahead of the weft yarn rise into loops, as the yarn approaches the fell, Fig. 14, and, when the reed has reached its full forward position, it strikes wire 48 and causes it to stand erect, as shown in Fig. 15. As a result of the straightening up of the wire, the loops of pile warps 26a raised over the wire, which were produced by the action of the weft yarn, become taut, so that these warps 50 engage the wire relatively tightly. The portions of the remaining pile warps 26b, which were raised by the action of the weft yarn, are then held in the form of low loops 27 against the rear face of wire 48 by the weft yarn, now fully beaten up.

It will be observed that the loops 27 and 29 rise between the same adjacent weft yarns 22 in the upper level of the fabric and, when the wire is withdrawn, loops 27 shift forward, so that 60 they come into full alignment with loops 29, as thus shown in Fig. 2. As each of the pile warps is formed into either a high loop 29 or a low loop 27 between each two adjacent weft yarns in the upper level, in the manner described, each transverse row of loops across the fabric is complete and without blank spaces. Each space in the pile surface defined by two adjacent weft yarns in the upper level and adjacent pairs of binder warps is filled by a single loop, either high or low, 65 rising from the backing in that space. The pile is, accordingly, dense and uniform, and, since a full row of pile elements is inserted in each operation of the loom, the loom works at top efficiency.

75 The height of the loops 27 formed by the ac-

tion of the weft yarns on the pile warps during the beat-up depends on the timing of the shedding motion and these loops may be given increased height by advancing the timing, so that the pile and stuffer warps reach parallelism with the binder warps in the central line of the shed, when the weft yarn is farther from the fell. Similarly, the height of loops 27 may be decreased by retarding the timing.

The formation of loops 27 by the action of the weft yarns on the pile warps does not occur in the second and fourth sheds of the cycle for the following reasons. A pile wire 48 is inserted into each of these sheds between the top and central lines of the shed and a weft yarn is inserted between the central and lower lines of the shed. During the insertion and beat-up of each wire, the wire is held at one end, so that it slopes slightly upwardly toward its free end. The binder warps lying in the central line of the shed are slightly higher than the pile warps 26b lying in the same line and the stuffer warps lie slightly below the pile warps in the central line of the shed. The top and bottom surfaces of the wire are both smooth and, as a result of the positioning of the warps and the smoothness of the surfaces of the wire, the wire does not act during the beat-up to push portions of the pile warps ahead of it. Similarly, the weft yarn travels in contact with the stuffer warps above it and the binder warps below it during the beat-up, so it cannot act on the pile warps.

In the foregoing, a form of the new method for weaving a fabric of simple construction has been described, but it will be apparent that the invention may be employed in the production of fabrics of more complex form, the construction of such fabrics being well-known.

I claim:

1. A method of weaving on a pile wire loom a pile fabric made up of stuffer warps, weft yarns crossing the stuffer warps above and below, binder warps crossing the weft yarns above and below and binding them against the stuffer warps, and pile warps held in place by portions thereof lying beneath weft yarns, which comprises maintaining the pile warps under slack tension and the remaining warps under relatively heavy tension, manipulating the warps to form a series of sheds, in which the warps lie in upper, central, and lower lines in different arrangements according to a cycle, the pile warps being displaced upwardly above the other warps in the lower line of a shed, inserting a weft yarn into each shed and simultaneously inserting a pile wire into each shed of the cycle in which there are pile warps in the upper line of the shed, beating up each inserted weft yarn together with the pile wire, when present, closing each shed when the weft yarn being beaten up is a substantial distance from the fell of the fabric, whereby, in the beating up of a weft yarn in a shed, in which pile warps are initially present in the lower line, the contact of the weft yarn being beaten up with such pile warps causes portions of such warps to be pushed up ahead of the yarn to form pile loops, and, after a plurality of wires have been inserted, withdrawing the inserted wires successively.

2. A method of weaving on a pile wire loom a pile fabric made up of stuffer warps, weft yarns crossing the stuffer warps above and below, two sets of binder warps crossing the weft yarns above and below and binding them against the stuffer warps, and pile warps held in place by

75 portions thereof lying beneath weft yarns, adjacent pile yarns being separated by a pair of binder warps, one from each set, which comprises maintaining the pile warps under slack tension and the remaining warps under relatively heavy tension, manipulating the warps to form a series of sheds in a cycle consisting of (1) a first shed, in which the binder warps of the first set are in a central line and all the other warps are in a lower line, (2) a second shed, in which certain pile warps are in an upper line, the remaining pile warps, the stuffer warps, and the binder warps of the first set are in a central line, and the binder warps of the second set are in a lower line, (3) a third shed, in which the binder warps of the second set are in a central line and all the other warps are in a lower line, and (4) a fourth shed, in which certain pile warps are in an upper line, the remaining pile warps, the stuffer warps, and the binder warps of the second set are in a central line, and the binder warps of the first set are in a lower line, the pile warps being displaced upwardly above the other warps in the lower line of the first and 10 third sheds of the cycle, inserting a weft yarn into each shed, the yarn being inserted between the central and lower lines in each shed of each cycle, inserting a pile wire between the upper and central lines in the second and fourth sheds 15 of each cycle, beating up each inserted weft yarn and the pile wire, when present in a shed, closing each shed when the weft yarn being beaten up is a substantial distance from the fell of the fabric, whereby, in the beating up of a weft yarn 20 in the first and third sheds, the contact of the weft yarn being beaten up with the pile warps in the lower line of the shed causes portions of the pile warps to be pushed up ahead of the weft 25 yarn to form pile loops, and, after a plurality of wires have been inserted, withdrawing the inserted wires successively.

3. A method of weaving on a pile wire loom a pile fabric including stuffer warps, weft yarns crossing the stuffer warps in a plurality of levels, binder warps crossing the weft yarns above and below and binding them against the stuffer warps, and pile warps held in place by portions thereof lying beneath weft yarns, which comprises maintaining the pile warps under slack 45 tension and the remaining warps under relatively heavy tension, manipulating the warps to form a series of sheds, in which the warps lie in different lines according to a cycle, pile warps selected in accordance with a pattern lying in the upper line of certain sheds and the lower line of certain sheds containing pile, stuffer, and binder warps with the pile warps displaced upwardly from the stuffer and binder warps in said line, inserting a weft yarn into each shed below 50 the central line thereof, inserting a pile wire into each shed containing pile warps in the upper line, the wire being inserted above the central line of the shed, beating up each inserted weft 55 yarn together with the inserted pile wire, when present, closing each shed containing pile warps in the lower line when the weft yarn being beaten up is a substantial distance from the fell of the fabric, whereby, in the beating up of a weft yarn 60 in a shed initially containing pile warps in the lower line, the contact of the weft yarn being beaten up with such pile warps causes portions of said warps to be pushed up ahead of the yarn to form pile loops, and, after a plurality of wires 65 have been inserted, withdrawing the wires suc-

cessively in the order in which they were inserted.

4. A method of weaving a pile fabric made up of a backing and pile warps having portions bound in the backing and other portions rising from the backing to form elements of a pile surface, the backing including interwoven filling yarns and binder warps, which comprises maintaining the pile warps under slack tension and the binder warps under relatively heavy tension, forming the warps into a series of sheds, certain of which contain binder warps and all the pile warps in the lower line with the pile warps displaced upwardly from the binder warps, inserting a weft yarn in each shed, beating up each inserted weft yarn, and closing each shed when the weft yarn being beaten up is a substantial distance from the fell, whereby, in the beating of a weft yarn in a shed initially containing pile warps in the lower line, the contact of the weft yarn being beaten up with such pile warps causes portions of said warps to be pushed ahead of the yarn to form pile loops.

5. A method of weaving on a pile wire loom a pile fabric made up of a backing formed of interwoven binder warps and filling yarns and pile warps having portions bound in the backing and other portions rising from the backing to form elements of a pile surface, which comprises maintaining the pile warps under slack tension and the binder warps under relatively heavy tension, forming the warps into a series of sheds, certain of which contain pile warps selected in accordance with a pattern in the upper line and others of which contain binder warps and all the pile warps in a lower line with the pile warps displaced upwardly above the binder warps, inserting a weft yarn in each shed and also inserting a pile wire in each shed containing pile warps in the upper line, beating up each inserted weft yarn together with the pile wire, when present, closing each shed when the weft yarn being beaten up is a substantial distance from the fell of the fabric, whereby, in the beating up of a weft yarn in a shed, in which pile warps are

initially present in the lower line, the contact of the weft yarn being beaten up with such pile warps causes portions of said warps to be pushed ahead of the yarn to form pile loops, and, after a plurality of wires have been inserted, withdrawing the wires successively in the order of their insertion.

6. A method of weaving a pile fabric made up of a backing containing interwoven filling and binder warps and a pile surface formed of pile warps having portions anchored in the backing and other portions raised above the backing, which comprises maintaining the pile warps under slack tension and the binder warps under relatively heavy tension, forming the warps into a series of sheds in a cycle, at least one shed of the cycle containing all of the pile warps and at least part of the binder warps in the lower line of the shed with the pile warps displaced upwardly from the binder warps, inserting a weft yarn in said shed, beating up the inserted weft yarn, and closing said shed when the weft yarn being beaten up is farther than normal from the fell of the fabric, whereby the contact of the weft yarn being beaten up with the slack pile warps beneath it causes portions of said pile warps to be pushed ahead of the yarn to form pile loops.
